Primary Examiner — John R Yeh(74) Attorney, Agent, or Firm — Vladimir Postnikov(57) CLAIM

The ornamental design for a bin and rake set, as shown and described.

DESCRIPTION

FIG. 1 is a front elevation view of a bin and rake set showing the new design;

FIG. 2 is a rear elevation view thereof;

FIG. 3 is a left side elevation view thereof;

FIG. 4 is a right side elevation view thereof;

FIG. 5 is top plan view thereof;

FIG. 6 is a bottom plan view thereof;

FIG. 7 is a perspective view thereof;

FIG. 8 is another perspective view thereof;

FIG. 9 is an enlarged view of portion 9 shown in FIG. 1;

FIG. 10 is an enlarged view of portion 10 shown in FIG. 1;

FIG. 11 is an enlarged view of portion 11 shown in FIG. 3; FIG. 12 is an enlarged view of portion 12 shown in FIG. 7; and,

FIG. 13 is an enlarged view of portion 13 shown in FIG. 7. The equal-length broken lines depict portions of the bin and rake set that form no part of the claimed design.

The dash-dot lines in FIGS. 1, 3, 7, 9, 10, 11, 12, and 13 illustrate the boundaries of the enlarged view indicators and form no part of the claimed design.
